GEORGE W. WHITTEMORE, OF BRISTOL, AND JULIUS H. WARNER, OF FORESTVILLE, CONNECTICUT, ASSIGNEES TO THE SESSIONS CLOCK COMPANY, OF FORESTVILLE, CONNECTICUT, A CORPORATION.

LOCKING DEVICE FOR DASH-CLOCKS.

1,158,611.

Specification of Letters Patent. Patented Nov. 2, 1915.

Application filed December 30, 1914. Serial No. 879,690.

To all whom it may concern:

Be it known that we, GEORGE W. WHITTEMORE, a citizen of the United States, residing at Bristol, in the county of Hartford and State of Connecticut, and JULIUS H. WARNER, a citizen of the United States, residing at Forestville, in the county of Hartford and State of Connecticut, have invented certain new and useful Improvements in Locking Devices for Dash-Clocks, of which the following is a specification.

Our invention relates to improvements in locking devices for dash clocks, and particularly to means for locking a clock to a dash-board for automobiles, such as what is known as a cowl dashboard, and the object of our improvement is simplicity and economy in construction and convenience and efficiency in use.

In the accompanying drawing:—Figure 1 is a front elevation of a clock and supporting ring equipped with our improved locking device. Fig. 2 is a side elevation of the same. Fig. 3 is a rear elevation of the same. Fig. 4 is a front elevation of the supporting ring. Fig. 5 is a side elevation of the front end of the clock. Fig. 6 is a fragmentary side elevation on an enlarged scale of certain parts shown in Fig. 2. Fig. 7 is a similar view of the same with the parts in an intermediate position. Fig. 8 is a rear elevation of the same. Fig. 9 is a rear elevation with the parts in the position shown in Fig. 6. Fig. 10 is a fragmentary view corresponding to Fig. 6 showing a latch spring provided with an integral pin.

Our improved locking device for dash clocks is adapted for use with any clock 10, such as shown, having a cylindrical casing, and a supporting ring 11 co-operating therewith. The supporting ring 11 comprises a flat body portion having holes 12 for screws by which it is mounted on the dashboard, a flange 13 extending forwardly from the inner edge of the said body portion, and a turned outer edge forming a rearwardly extending rim 14.

The inner, forwardly extending flange 13

has on opposite sides a slot for a bayonet joint comprising a short longitudinally directed entrance portion 15 extending rearwardly from the edge and a lateral portion 16 extending circumferentially, the same as shown extending righthandedly or clockwise.

In the body portion of the ring 11, as shown in the left side, and slightly above the entrance portion 15 of the slot mentioned, so as to be out of alignment therewith is a hole 17 in which is positioned the front end of a pin 18 that slides back and forth therein, and which is mounted on the latch spring 19. The latch spring 19 is mounted on the rear face of the body portion of the ring 11, is formed of flat spring material, is secured by its upper end by rivets 20, positioned appreciably above the bayonet slot 15, extends downwardly adjacent the inner face of the said body portion, being suitably curved along the edges to conform to the shape thereof, has the pin 18 secured to the lower end portion, and adjacent the said lower end portion has a pair of inwardly directed arms, respectively a lower arm 21 and an upper arm 22, separated by a slot 23. The arms 21 and 22 overhang the inner wall of the inner cylindrical flange 13. That is to say, the arms 21 and 22 extend inwardly into the interior space enclosed by the ring 11. The latch spring 19 is so formed and secured that the lower end portion is held in abutment with the rear face of the body portion of the ring 11 so that it tends to hold the pin 18 projected forwardly to the maximum extent, and the same is held in such position normally. The pin 18 may be a separate piece, secured to the spring 19 by riveting or as shown in Fig. 10 the pin 18 may be integral with the spring 19, and formed by a forward projection of the material of the spring. The lower arm 21 is back of the entrance portion 15 of the bayonet slot, and in the same axial plane. The slot 23 is a fit for a locking pin 24 on the clock 10, and when the said pin is positioned therein the clock 10 is locked in the ring 11, against rotative movement.

Rotation in the clockwise direction is prevented by the upper arm 22 and in the counter-clockwise direction by the lower arm 21, in engagement with the locking pin 24. Rotation in the clockwise direction is also limited by the end of the lateral branch 16 of the bayonet slot in coöperation with the radial pin 25 on the clock 10, so that in some cases the upper arm 23 may be dispensed with.

The clock 10 comprises a cylindrical body portion 26 of appreciable length and a head portion 27 at the front end enlarged relatively to the said body portion 26 provided on the front end with a still further slightly enlarged rim 28. The said head portion 27 fits in the forwardly extending flange 13 in the ring 11, is provided with a pair of radial pins 25, already mentioned, suitable for co-operating with the bayonet slots 15, and on the left side is provided with the locking pin 24, also already mentioned. The locking pin 24 extends rearwardly from the rear face of the head, so as to be off-set to one side relatively to the body portion 26, and is positioned just to the rear of and in the same radial plane as the corresponding radial pin 25.

In entering the clock 10 into supporting position within the ring 11 the head portion 27 is entered within the flange 13 and with the radial pins in registration with the entrance portion 15 of the bayonet slots. This operation brings the locking pin 24 into abutment with the lower arm 21 of the latch spring 19. As the clock 10 is pushed rearwardly the arm 21 and the lower end portion of the spring 19 are pushed rearwardly correspondingly, until the radial pins 25 are brought into registration with the lateral branch slots 16, so that turning the clock brings the radial pins into engagement with the said branch slots 16. The engagement of the radial pins 25 with the lateral slots 16 serves as securing means for generally securing the clock 10 in position in the ring 11.

During the turning movement described the locking pin 24 slips off from the lower arm 21 into the slot 23, between the two arms, and the spring 19 is free to return to its normal position, with the lower end in the maximum forward position.

The engagement of the locking pin 24 with the lower arm 21 prevents turning the clock 10 back to the unlocking position. By providing the second arm 22 and having the locking pin 24 a good fit for the slot 23 the clock 10 is securely locked in position in such a manner as to prevent rattling or free play.

In order to release the clock the pin 18, which serves as a latch handle, is pushed rearwardly so that the locking pin 24 can

pass under the lower arm 21 and the clock is turned in the counter-clockwise direction 65 until the radial pins 25 are in registration with the entrance slots 15, when the clock 11 is free to be pulled out from the supporting ring.

It will be noted that the only portion of 70 the locking device that is visible from the front is 12 the latch handle or operating pin 18, and there are no indications from the front view of the manner of removal of the clock, the locking device being essentially in 75 the class of a secret lock. Furthermore, in placing the clock in locking position there is no manipulation whatsoever of the locking device on the part of the operator and in removing the clock the only part of the lock- 80 ing device operated on is the pin 18.

While as shown and described the locking pin 24 and the corresponding radial pin 25 on the clock 10 are in the same axial plane, and the parts on the ring 11 that coöperate therewith in the initial movement of bringing the parts to the locking position consisting of the lower arm 21 on the latch spring 19 and the entrance portion 15 of the bayonet slot are also in the same plane, and 90 these planes coincide during such initial movement, it will be understood that the bayonet joint feature of our device, comprising the radial pins 25 and the bayonet slots may if desired be located at different 95 positions relatively to the locking device, consisting of the locking pin 24 and the latch spring 19. Also, while it is preferred to have two bayonet joints, it is understood that in some cases one of these may be 100 omitted.

We claim as our invention:—

1. A dash device and clock combination comprising a circular dash device and a clock having overlapping cylindrical portions, the said dash device having a plane and radial body portion provided with a rearwardly turned edge at the periphery, a locking device comprising a spring device on the said dash device and a pin on the 110 said clock, and the said spring device being housed in the space inclosed by the said rearwardly turned edge.

2. A ring and a clock fitting therein, holding means operative by a limited relative 115 longitudinal and rotative movement of the said ring and clock, locking means serving to lock the said ring and clock against return rotative movement responsive to such relative longitudinal and rotative movement 120 thereof, the said ring comprising a flat, annular body portion, and a releasing device for the said locking means comprising a push pin extending through the said body portion.

3. A dash and clock combination compris-

ing a dash member and a clock member having overlapping cylindrical portions, the said dash member comprising a flat radial face extending outwardly from its overlapping portion, the said clock having a flat, radial face extending inwardly from its overlapping portion, and a locking device comprising a pair of coöperating engaging parts, positioned one on each of the said flat radial faces.
